UNITED STATES PATENT OFFICE.

ALEXANDER THOMAS STUART AND GUY NOVERRE MIDDLETON, OF TORONTO,
ONTARIO, CANADA, ASSIGNORS TO THE TORONTO POWER COMPANY LIMITED,
OF TORONTO, ONTARIO CANADA, A CORPORATION OF ONTARIO.

APPARATUS FOR USE IN CONNECTION WITH CHEMICAL AND PHYSICAL OPERATIONS.

1,417,585.

Specification of Letters Patent. Patented May 30, 1922.

Application filed July 5, 1917, Serial No. 178,702. Renewed December 27, 1920. Serial No. 433,425.

To all whom it may concern:

Be it known that we, ALEXANDER THOMAS STUART and GUY NOVERRE MIDDLETON, both subjects of the King of Great Britain, residing at the city of Toronto, in the county of York and Province of Ontario, Dominion of Canada, have invented certain new and useful Improvements in an Apparatus for Use in Connection with Chemical and Physical Operations; and we hereby declare that the following is a full, clear, and exact description of the same.

This invention relates to an apparatus for use in connection with chemical and physical operations requiring high temperatures and pressures, and the object of the invention is to so design this apparatus that it will be capable of heat conservation, close temperature regulation, high thermal input per unit surface area, mechanical resistance to high pressures, the selective recovery of the desired products, and the automatic retreatment of the undesired products, this object being attained by the use 20 of a closed reaction chamber, whose wall or walls is or are of material of high electrical resistance, and into which, matter, to be acted on, is admitted, combined with a suitably-trapped condenser, or a battery of 25 30 suitably-trapped condensers, connected in series, through which the products may pass from the reaction zone.

The reaction chamber is preferably surrounded by a protecting jacket, into which an inert gas of high dielectric properties, may be introduced under pressure, to counterbalance the pressure within the reaction zone.

The reaction chamber may take a tubular 40 form, and may be constructed of standard or special tubing preferably iron or steel adaptable to ordinary electrical circuits or transformers, the shape and dimensions of the reaction chamber being determined by 45 the purposes for which the apparatus is intended, and a heat insulator being interposed between the reaction chamber and the protecting jacket, to prevent heat being radiated from the reaction chamber to the 50 jacket. The heat insulator may be asbestos, mineral wool or other material of a granular or fibrous nature, having voids into which the pressure balancing medium may enter.

The condensers may also take a tubular 55 form, such as may be constructed of standard or special tubing or piping, and are surrounded with jackets to maintain the desired condensing temperatures, each condenser having an individual trap through 60 which its condensate may be taken off.

The feed for the reaction chamber preferably enters through the trap of one of the condensers to enable the condensate therein and the matter to be treated to 65 mingle before passing into the reaction zone.

Electrical conductors of the heating circuit are connected with the reaction chamber, and the flow of the current is so regulated as to heat it to the desired temperature, this temperature being conserved within the reaction chamber by the heat insulator. The reaction chamber is provided with a contact making and breaking pyrometer, to maintain a close temperature 70 regulation of the reaction apparatus, and a check may be maintained on this temperature regulation by utilizing the difference in the ratio of expansion between the reaction chamber and jacket to operate a 75 circuit breaker in the circuit, such expansion arrangement constituting in itself a 80 thermostatic control.

In the drawings:—

Fig. 1, represents a longitudinal sectional 85 elevation of a preferred form of apparatus;

Fig. 2, is a similar view taken at right angles to Fig. 1;

Fig. 3, is a detail view of the reaction 90 chamber; and,

Fig. 4, is a similar view of a modification of the reaction chamber.

Like characters of reference refer to like parts throughout the specification and drawings.

The reaction chamber *a*, which may preferably take a tubular form, and be of any suitable dimensions and cross-sectional shape, is surrounded by a corresponding jacket *b*, capable in itself of withstanding 100 high pressures. This jacket is provided with an inlet *e*, through which a pressure-balancing medium may be admitted, to occupy the space between the jacket and the reaction chamber. Contained between the 105 jacket and the reaction chamber, is a heat insulator *c*, to prevent the radiation of heat from the reaction chamber to the jacket.

The presence of this insulator is advisable, as the jacket should be kept at as low a temperature as possible, to enable it to retain its full tensile strength.

- 5 Connected with the reaction chamber are intake and offtake pipes *f* and *g* respectively, and connected with the intake and offtake pipes are the electrical conductors *f'* and *g'* of the heating circuit, the flow 10 of which is so regulated as to heat the reaction chamber to the desired temperature, this heat being conserved within the reaction chamber by the presence of the heat insulator *c*.
 15 The reaction chamber is provided with a contact making and breaking pyrometer *h* which operates a mechanical contact or circuit breaking device *j*, by which the heating circuit formed by the conductors 20 *f'* and *g'* may be made and broken.

The difference in the ratio of expansion between the reaction chamber and the jacket may be utilized to operate a mechanical contact *i*, *i'* for making and breaking 25 an electrically-controlled circuit, by which the same heating circuit may be made and broken, such an expansion arrangement constituting in itself a thermostatic control.

Coacting with the reaction chamber is a 30 condenser or a set of condensers connected in series.

In Fig. 1 of the drawings, each reaction chamber is shown to be connected through a set of four condensers, numbered 3 to 6 inclusive, and in Fig. 2, is shown a battery of six reaction apparatus, the condensers of each set being connected in series, with their respective reaction chamber.

In Fig. 1, each condenser 3, 4, 5 and 6 is 40 shown to be provided with a trap *3^a*, *4^a*, *5^a* and *6^a* respectively, each of the condensers being preferably of a tubular formation of any suitable cross-sectional shape and dimensions.

- 45 Condenser 3 is connected not only with the offtake pipe *g* but also, although less directly, with the intake pipe *f*, in the sense that at the bottom of the condenser 3 is a drainage pipe *3^c* extending down to approximately the bottom of the trap *3^a*. The 50 top of this condenser is connected by a coupling pipe *3^f*, with the top of the condenser 4. The lower end of the condenser 4 extends down into the trap *4^a*, the top of which is connected by a pipe *4^c* with the condenser 5, above its trap *5^a*, the top of the condenser 5 being connected by a coupling pipe *5^f*, with the top of the condenser 6, the lower 55 end of which leads down into the trap *6^a*.
 60 The offtake pipe *g* is connected with the condenser 3 above the level of the trap *3^a*, and the intake pipe *f* extends into the trap near the top thereof. Leading into the trap *3^a*, near the bottom thereof, is the feed pipe *h*, by which the matter to be treated in the

reaction chamber is delivered into the trap to pass through the intake pipe *f* to the reaction zone, the trap *3^a* being provided with a gauge glass *j*.

When fluid matter, such as hydrocarbons, 70 is to be treated in the reaction chamber, it is delivered through the feed pipe *h* into the trap *3^a*, filling the trap until it attains the level of the top of the intake pipe *f*, through which it then flows into the reaction chamber *a*.

The reaction chamber shown in Fig. 3 of the drawings, is of a U-bend type, and its wall or walls is or are of material of high electrical resistance, but the reaction chamber may be of any other type, such as that shown in Fig. 4.

The conductors *f'*, *g'* of the heating circuit are connected with the intake pipe *f* and offtake pipe *g*, respectively, and the current circuiting from the conductor *f'* to the conductor *g'*, by means of the reaction chamber, heats its wall to any desired temperature.

The matter to be treated, when it enters 90 the reaction zone, undergoes destructive decomposition, and passes through the offtake pipe *g* in the form of gases to the condenser 3.

The heavier hydrocarbon products, whose 95 boiling point ranges are necessarily higher than those of the lighter hydrocarbon products, condense at higher temperatures than such lighter hydrocarbons, and, should it be necessary to retreat any of the heavier hydrocarbon products, the condensing temperature of the condenser 3 may be set to take off such heavier products in the form of condensates, and run them back through the trap *3^a*, in which they will mingle with the matter to be treated as it passes into the reaction zone.

The hydrocarbon fractions with the next higher boiling points may be taken off as condensates through the trap *4^a*, and so on 110 through the traps *5^a* and *6^a*.

To control the character of the hydrocarbons taken off through these different traps, each condenser 3, 4, 5 and 6 is provided with a jacket *3^g*, *4^g*, *5^g* and *6^g*, respectively, to 115 contain the condensing atmosphere, the temperature of which is different for each condenser, so that the different condensates may be simultaneously taken off from the condensers and in this way, the necessity for 120 fractional cracking or distillation may be avoided.

As shown in Fig. 1, the jacket *b* is provided with a mechanical contact *i*, and the reaction chamber is provided with a mechanical contact *i'*. Connected with the contacts *i* and *i'* are electrical conductors *j*, *j'*, controlling the circuit breaker *j³* for the main heating circuit *f'*, *g'*, so that in the event of the temperature in the reaction 130

- chamber rising above the degree at which the mechanical contacts i' , i'' are set, these contacts will come together and close the circuit through the circuit breaker j^3 to open 5 the main heating circuit f' , g' . The contact making and breaking pyrometer h' , by means of a controlled circuit k' , k'' , will also actuate the circuit breaker to open the main heating circuit.
- 10 In the destructive decomposition of hydrocarbons, it is necessary to maintain high pressures in the reaction zone, such pressures approximating eight to ten atmospheres, and sometimes higher, and in such 15 cases, it is necessary to counterbalance the pressure within the reaction zone by a corresponding pressure on the outside of it, as otherwise, the reaction chamber would be liable to rupture, as a result of such internal 20 pressure, owing to its reduced tensile strength, resulting from its high temperature.

The counterbalancing pressure within the jacket may be obtained either by passing 25 some of the matter to be treated into the chamber formed by the jacket and the reaction zone, if the conditions of the process and the apparatus warrant it, or, when this is not possible, a counterbalancing pressure 30 may be obtained by forcing a gaseous agent into the space between the reaction chamber and the jacket, through the inlet e , the presence of such counterbalancing pressure lowering the tendency to rupture to a negligible 35 quantity.

Having thus fully described the nature of our invention, what we claim as new and desire to secure by Letters Patent, is:—

1. An apparatus for use in connection 40 with chemical and physical operations requiring high temperatures and pressures, comprising a closed reaction chamber whose wall is of material having high electrical resistance, an intake and an offtake therefor, 45 electrical conductors establishing a circuit through the wall of the reaction chamber to create the desired reaction temperature, and pressure resisting means surrounding the reaction chamber to support it against internal pressure.

2. An apparatus for use in connection with chemical and physical operations requiring high temperatures and pressures, comprising a closed reaction chamber whose wall is of 55 material having high electrical resistance, an intake and an offtake therefor, electrical conductors establishing a circuit through the wall of the reaction chamber to create the desired reaction temperature, a jacket surrounding the reaction chamber, and a pressure resisting fluid between the jacket and reaction chamber to counterbalance the internal pressure of the reaction chamber.

3. An apparatus for use in connection 60 with chemical and physical operations re-

quiring high temperatures and pressures, comprising a closed reaction chamber whose wall is of material having high electrical resistance, an intake and an offtake therefor, 70 electrical conductors establishing a circuit through the wall of the reaction chamber to create the desired reaction temperature, a jacket enclosing the reaction chamber, heat insulation between the jacket and the reaction chamber, and a pressure fluid filling the 75 interior of the jacket and the voids in the heat insulation to counterbalance the internal pressure within the reaction chamber.

4. An apparatus for use in connection with chemical and physical operations requiring 80 high temperatures and pressures, comprising a closed reaction chamber whose wall is of material having high electrical resistance, an intake and an offtake therefor, electrical conductors establishing a circuit through the 85 wall of the reaction chamber to create the desired reaction temperature, and thermostatic means for opening and closing the circuit through said conductors controlled by the 90 temperature of the reaction chamber.

5. An apparatus for use in connection with chemical and physical operations requiring high temperatures and pressures, comprising a closed reaction chamber whose wall is electrically resistant, an intake and an offtake 95 therefor, electrical conductors establishing a circuit through the wall of the reaction chamber to create the desired reaction temperature, and thermostatic means controlled by the temperature of the reaction chamber 100 governing the circuit of the current through the conductors.

6. An apparatus for use in connection with chemical and physical operations requiring high temperatures and pressures 105 comprising a treating chamber of tubular construction whose wall is of material having high electrical resistance and capable of 110 withstanding high temperatures and pressures, an intake for admission thereto of the matter to be treated, an offtake for egress therefrom of the products of the reaction, and electrical conductors establishing a circuit through the wall of said chamber to create the desired reaction temperature.

7. An apparatus for use in connection with chemical and physical operations requiring high temperatures and pressures comprising, a treating chamber of tubular construction whose wall is of material having high electrical resistance and capable of 120 withstanding high temperatures and pressures, an intake for admission thereto of the matter to be treated, an offtake for 125 egress therefrom of the products of the reaction, electrical conductors establishing a circuit through the wall of said chamber to create the desired reaction temperature, and a jacket surrounding the reaction chamber,

- having an inlet for admitting a pressure balancing medium between the reaction chamber and the jacket to counterbalance the pressure within said chamber.
5. 8. An apparatus for use in connection with chemical and physical operations requiring high temperatures and pressures comprising, a treating chamber of tubular construction whose wall is of material having high electrical resistance and capable of withstanding high temperatures and pressures, an intake for admission thereto of the matter to be treated, an offtake for egress therefrom of the products of the reaction, electrical conductors establishing a circuit through the wall of said chamber to create the desired reaction temperature, a jacket surrounding the reaction chamber, having an inlet for admitting a pressure balancing medium between the reaction chamber and the jacket to counterbalance the pressure within said chamber and a heat insulator interposed between the jacket and the reaction chamber.
10. 9. An apparatus for use in connection with operations requiring the application of high temperatures to fluids, a treating chamber in the form of a resistance tube, means for feeding the fluid thereto, leads for bringing an electric circuit into conductive relationship with said tube, a circuit opener in one of said leads, and means for operating said circuit opener to open said circuit.
15. 10. An apparatus for the heat treatment of fluid mixtures comprising a tubular retort provided with a feed intake and a vapor offtake and having a wall sufficiently low in electrical conductivity to act as a resistor, said wall being capable of withstanding high temperatures and pressures, means for passing a current through said wall to heat the retort to a relatively high temperature, means for feeding a fluid mixture to said intake, and means for recovering desired products from the fluids leaving said offtake.
20. 11. An apparatus for the heat treatment of fluid mixtures comprising a retort of heavy walled metal pipe encased in heat insulation and having sufficiently low electrical conductivity to act as a resistor, said retort being provided with a feed intake and a vapor offtake, means for feeding a mixture of fluids to said intake and condenser means connected both to said offtake and to said intake, there being a return trap device connecting said condenser with said intake.
25. 12. An apparatus for the heat treatment of fluid mixtures comprising a retort of heavy walled metal pipe encased in heat insulation and having sufficiently low electrical conductivity to act as a resistor, said retort being provided with a feed intake and a vapor offtake, means for feeding a mixture of fluids to said intake and condenser means connected both to said offtake and to said intake, there being a return trap device connecting said condenser with said intake.
30. 13. An apparatus for the heat treatment of fluid mixtures comprising a retort of heavy walled metal pipe encased in heat insulation and having sufficiently low electrical conductivity to act as a resistor, said retort being provided with a feed intake and a vapor offtake, means for feeding a mixture of fluids to said intake and condenser means connected both to said offtake and to said intake, there being a return trap device connecting said condenser with said intake.
